UNITED STATES PATENT OFFICE

2,637,456

APPARATUS FOR RELATIVELY CONTINUOUSLY RECEIVING MATERIAL AND IN-TERMITTENTLY DISCHARGING THE SAME

Lloyd G. Felderman, Franklin, Pa., assignor to
Joy Manufacturing Company, Pittsburgh, Pa.,
a corporation of Pennsylvania

Application November 18, 1948, Serial No. 60,738

15 Claims. (Cl. 214—83.14)

1

My invention relates to material receiving, storing and discharging apparatus, and more particularly to such apparatus particularly, but by no means exclusively, adapted to use with mineral vein-disintegrating and disintegrated material-delivering apparatus which is capable of relatively continuously delivery of material. Its various aspects will hereinafter appear.

"Continuous miners" of a recently developed type disintegrate a mineral vein and deliver at their discharges the disintegrated mineral—as, for example, but without limitation thereto, coal—in such a manner that, while there are brief interruptions between the delivery of the mineral resulting from the disintegration of a given upright band and the delivery of the mineral resulting from the disintegration of the next adjacent band, and longer interruptions—though still brief ones—between the completion of the disintegration of one transverse series of upright bands and the initiation of the attack on a subsequent series, there is nevertheless a delivery of relatively large quantities of mineral, with such minor interruptions of continuity of discharge, that a serious problem is presented by the fact that load reception is intermittent with the transport devices best adapted to handle the product of such "Miners." When continuity of discharge is possible, the problem is even more acute.

If, to present a simple example, we assume a "Miner" to have an average discharge rate of a ton per minute, and a "Shuttle car" can make a round trip, including discharging time, from the "Miner" discharge back to the same again, in three minutes, it will be apparent that some provision for the storage of three tons of coal must be made in order that the "Miner" can continue its attack on a mineral vein while the "Shuttle car" is traveling from the "Miner" to its discharge point, effecting discharge of its load, and returning to the "Miner."

The provision of a suitable storage device adapted to meet such conditions is one of the objects of my invention. Such a storage device must have provision for the discharge of its received load. To that end it will desirably embody a conveyor: belt, flight or other. It must have storage capacity for the material discharged by the "Miner" in the period of absence of the "Shuttle car." This may be provided by the use of a hopper car, by the use of a belt conveyor with stationary side boards, or by the use of a belt conveyor without side boards, when longitudinal dimension of the device is not a vital

factor. One characteristic of any such device is, however, that so long as the conveyor continues to move (circulate—with the types mentioned) there will be spread over the top run thereof a layer of disintegrated mineral, thick or thin depending on the rate of conveyor travel; and, when a thin layer of material remains on the conveyor at the end of a discharge period, and the conveyor is much slowed down to receive and distribute a new load, there will necessarily have to be made some disposition of this thin layer, for otherwise it will be dumped on the mine bottom. It can, in accordance with my invention, be very satisfactorily gotten rid of by delivering it to a "Car" which has been receiving a load, while preventing its renewal by cutting off the access of new material to the conveyor and providing for its temporary retention or storage while the conveyor is cleared. According to a preferred embodiment of my invention there is provided means for temporarily intercepting the discharge from the "Miner" while the conveyor clears itself. Such a means may desirably be arranged to enable the discharge of the temporarily held back material onto the conveyor, and to be moved to a position in which the discharge of material from the "Miner" shall have free access to the material storage means, though in the event of a large mass of material being stored, and the use of a narrow belt with side boards or a wider belt without side boards, a metering function might be needed before the interception was fully discontinued. The intercepting device may desirably be superimposed on the material receiving, distributing and discharging means adjacent the material receiving end of the latter, actually overlying, in a preferred embodiment, the conveyor of such means, and may be so constructed and arranged as to be rendered operative to effect material interception, or to discontinue such interception at will.

Reverting to the objects of my invention, it is, then, a primary object to provide an improved material-receiving, storing and discharging apparatus so constructed and arranged that the distribution of a thin layer of material over the bottom thereof during the final stages of unloading therefrom of an accumulated load may be prevented. Another object of the invention is to provide an improved material receiving, storing and discharging apparatus having in combination with its means for distributing the material received thereby during loading thereof throughout its length at an appropriate rate and for unloading the material rapidly when it is desired to

discharge it, of means for preventing material which may continue to be delivered to one end of the apparatus from being spread throughout its length during the final stages of unloading of material therefrom. A further object is to provide an improved material receiving, storing and discharging apparatus having improved material handling and controlling apparatus associated therewith, whereby material may be moved from one portion thereof for discharge while material being delivered to another portion thereof may be intercepted and stored where it falls, out of the field of operation of the material conveying means which forms a portion of such apparatus. Still another object of the invention is to provide an improved material receiving, storing and discharging apparatus embodying an improved combination of conveying and distributing means and temporary storage means for receiving and maintaining in a position in which it is not engageable by the material conveying and distributing means a substantial quantity of material and for then dumping it on the material conveying and distributing means. A further object is to provide an improved material intercepting apparatus. Other objects and advantages of the invention will hereinafter more fully appear.

In the accompanying drawings in which one illustrative embodiment which my invention may assume in practice is shown for purposes of illustration,

Fig. 1 is a plan view of a material receiving storing and discharging apparatus constructed in accordance with the illustrative embodiment of the invention.

Fig. 2 is a side elevational view of the structure shown in Fig. 1.

Fig. 3 is an enlarged cross sectional view on the plane of the section line 3—3 of Fig. 2.

Fig. 4 is a view similar to Fig. 3, showing the parts in a different position.

Fig. 5 is an enlarged fragmentary longitudinal sectional view on the plane of the section line 5—5 of Fig. 1.

Fig. 6 is a generally diagrammatic view showing the invention in use.

Figs. 7, 8 and 9 are generally diagrammatic views showing respectively conditions when the hopper is nearly fully loaded, a relatively late portion of the discharge phase of the operation of the apparatus, and the condition of the apparatus at the conclusion of discharge and just before an intercepted mass of material is dumped onto the material receiving and distributing conveyor.

The preferred embodiment of the invention is shown incorporated in an apparatus 1, which is quite similar in construction, except as herein-after explained, to a "Shuttle car." This construction includes a body 2 having a wide material-receiving portion 3 and having, in contrast to the rubber tired wheels of the usual "Shuttle car," motor driven, tractor tread, supporting means 4, one at each side and each driven by a motor 5, one of said motors being shown in Fig. 2; and the propulsion of the apparatus 1 is controllable by any suitable mechanism, herein generally designated 6, by which the tractor tread supporting means 4 can be independently or simultaneously driven. The apparatus 1 is adapted to move along behind a "Continuous miner" M, see Fig. 6, and to receive the disintegrated material which the latter discharges. This close adjacency may be maintained by the propulsion means of the apparatus 1, or could be effected by

the use of a suitable draw bar or equivalent connection between the "Miner" and the apparatus 1. The "Continuous miner" M may be of various forms, but is shown for purposes of illustration as similar to the structure disclosed and claimed in the copending application of Samuel Leven, Serial No. 19,698, filed April 8, 1948, which application is owned by my assignee. It includes a disintegrating apparatus 7, a driving motor therefor 8, suitable feeding, retracting, laterally positioning and vertically swinging means—not all shown in this present case, but fully shown in the application above mentioned—and adapted to permit the "Miner" to attack and disintegrate the mineral vein in a plurality of upright sections of desired length or height, width and depth. The "Miner" has its own delivery conveyor 9 at the rear end thereof, and this conveyor is adapted to discharge to the apparatus 1 (see Fig. 6).

The apparatus 1 has a conveyor 11, shown as a flight conveyor, and including flights 12 moved by flight-moving chains 13 driven by sprockets 14 on a transversely extending shaft 15, driven through worm and worm wheel mechanism 16 and a flexible connection 17 by a motor 18 through a clutch controlled reduction mechanism 19. Drive of the conveyor by the motor 18 may be controlled by a friction clutch as in the Charles F. Ball application, Serial No. 760,541, filed July 12, 1947, now abandoned, and owned by my assignee, or by any suitable switch mechanism, not shown.

The conveyor 11 extends throughout the bottom of the body 2, and through a vertically adjustable discharge section 21, tiltable about an axis at 22 and having the elevation of its discharge end 23 adjustable by a hydraulic jack device 24 supplied with hydraulic fluid under pressure from any suitable source, as, for example, the usual motor driven pump (not shown) customarily found on "Shuttle cars," under the control of a valve device 26. The pump may for example be arranged and driven as in the Ball application above mentioned. The conveyor 11 is guided at its end remote from the shaft 15 as at 27, and extends throughout the full length of the body 1.

For the purpose of preventing access of material discharged by the delivery conveyor 9 to the conveyor 11, when it is desired that such delivery shall not take place, I have provided intercepting means shown in Figs. 1, 2, 3, 4, 5, 8 and 9. This includes a pair of material supporting plates, 35, 36, each secured to a longitudinally extending blocklike element 37 extending for the full length, longitudinally of the apparatus, of the plates 35 and 36, and each having secured to it a pair of horizontal bars or legs which, in the position of the plates 35, 36 with their edges in substantial contact with each other, extend substantially for the full transverse width of the bottom portion of the body 2. The legs associated with the plate 35 are numbered 38, and those associated with the plate 36 are numbered 39. These legs are guided in pairs in guide openings 40, of rectangular cross section, in open-ended boxlike elements 41 arranged beneath the bottom plate 42 of the body 2. It will be evident that the legs 38, 39 guide the plates 35, 36 for movement rectilinearly towards and from each other. The plates extend through slots or openings 43 in the sloping side walls 44 of the body 2, and are adapted to be slid into contact with each other, as shown in Figs. 1 and 3, and into

withdrawn position, as shown in Fig. 4, by suitable hydraulically controlled link and lever mechanisms 45. Bearing blocks 46 supported on the outer side walls of the body 2 rotatably support longitudinally extending shafts 47 carrying near their centers arms 48 to which there is pivotally connected at 49 an eye 50 on a piston rod 51 extending from a piston 52 reciprocable in a cylinder 53 pivotally connected at 54 to the body 2. Near their ends, the shafts 47 carry arms 55 pivotally connected at 56 to links 57 which are in turn pivotally connected at 58 to the block elements 31. When the pistons 52 are at the inner ends of the cylinders 53, it will be evident that the mechanisms 45 position the plates 35, 36 close to each other. When the pistons 52 are moved outwardly relative to the cylinders 53, the plates 35, 36 are drawn apart, as shown in Fig. 4. Any suitable means for supplying fluid to the cylinder and piston mechanisms for controlling the positions of the plates 35, 36 may be provided, as for example, a source of hydraulic fluid under pressure as above described, and a control valve 60.

The mode of operation of the invention, as so far described, may be understood most readily by reference to Figs. 1, 3, 4, 6, 7, 8 and 9. The hopper car is shown, in Fig. 1, as being empty, a condition which may be brought about at any time by interrupting the operation of the "Continuous miner", with which the apparatus described is associated, and continuing to circulate the conveyor 11. In this view, the plates 35, 36 are shown in contiguity to each other. Ordinarily, with the hopper completely empty, these plates will be withdrawn to the position shown in Fig. 4, and loading of material into the car will be commenced. Then, when the "Miner" continues to deliver material into the hopper car body 2, it will be allowed to fall to the bottom 40 of the latter, and by appropriate manipulation of the controller for the conveyor driving motor 18, or preferably of a clutch, the load will be distributed along the length of the body 2 until the body is fully loaded. Fig. 7 represents diagrammatically the loaded state of the apparatus. Both the body 2 and the discharge section 21 are loaded. According to one example, perhaps three minutes may be required to load the body. In Fig. 8, the flight conveyor 11 has been utilized to discharge all of the load which has been deposited on it and distributed throughout its length. However, material has continued to fall onto the body as the load was discharged, so a thin layer of material, as shown at 61, is spread over the bottom of the body. The operator will then cause the plates 35 and 36 to be moved together to the position of Figs. 1 and 3, and Fig. 8 shows conditions just as the plates have been moved together and just as the discharged material from the "Miner" begins to fall on the plates. The conveyor 11 will be used to discharge the layer 61 to a "Shuttle car" or the like, while the material continues to fall on the plates 35 and 36, with the result that a condition as represented in Fig. 9 will be attained. When there is no material spread over the bottom of the body or in the discharge section 21, the plates will be separated, as shown in Fig. 4, and the material will be dumped in the body 2, the conveyor being first stopped or at least slowed down. Loading of the body will then proceed.

It is unnecessary to defer the moving of the plates 35 and 36 together until the main load has been fully discharged and a thin layer of

material extends throughout the full length of the bottom of the conveyor, as indicated in Fig. 8. Instead, soon after the level of the material at the end of the body 2 to which discharge takes place falls below the position of the plates 35 and 36, these may be advanced towards each other and caused to intercept and store material. This is not, however, probably the best way of procedure, and it is thought preferable to advance the plates towards each other only when the condition of the material in the conveyor approximates that of Fig. 8.

Referring to Fig. 6, it will be seen that the discharge conveyor 9 of the "Miner" is delivering material to the apparatus 1, and that a "Shuttle car" is positioned with its load receiving end under the end of the discharge section 21 of the apparatus which forms the subject matter of this present invention.

Having in mind the characteristic of "Shuttle cars," and that these may be loaded rather rapidly by moving the conveyors which extend along their bottoms at an appropriate rate, it will be understood that if the "Shuttle car" and the hopper car are of generally similar capacity and construction, it will be possible, by suitably operating their conveyors, to transfer the accumulated load from the hopper car to the "Shuttle car," to complete the filling of the latter, and to clear the conveyor of the hopper car in a relatively short time.

Since the plates 35 and 36 are relatively close to the end of the body 2 to which material is adapted to be discharged, it will be understood that they may also cause some material to be stored against the sloping wall 63 of the body 2, thereby providing a greater storage capacity for material. This is indicated in Fig. 9.

Notwithstanding the presence of low sloping wall 63, the body is open from end to end in the sense that it is not divided up into a plurality of longitudinally serially arranged compartments.

It will be evident that the invention is adapted to permit the use of a conveyor arrangement essentially the same as is common to "Shuttle cars," without special modifications thereof, for the distribution and discharge of material delivered to the hopper car, and that through the superpositioning on the more or less conventional structure mentioned of the intercepting and storage means illustrated by the plates 35 and 36 and the operating means therefor, it will be possible to prevent the discharge onto the mine bottom of a layer of material, such as is shown in Fig. 8, during the reception of a new load by the hopper car after the material with which it had previously been loaded has been discharged. It will be apparent, therefore, that the invention possesses the advantage not only of effectively solving a serious problem, but that in addition it permits the solution of the problem with minimum departure from relatively standard arrangements. The caterpillar support is provided in place of a wheeled support to enable greater body capacity and to facilitate maneuverability. The general body construction may be made virtually the same as that of the "Shuttle cars" to which the hopper apparatus is to discharge material, the essential change being only the addition of a simple, rugged, and positively operable intercepting means.

While there is in this application specifically described one form which the invention may assume in practice, it will be understood that

this form of the invention is shown for purposes of illustration and that the invention may be modified and embodied in various other forms without departing from its spirit or the scope of the appended claims.

What I claim as new and desire to secure by Letters Patent is:

1. In an apparatus of the character described, including a body open from end to end for receiving and storing material and conveyor means associated with said body and extending along the bottom of said body inside the latter for moving material received at one end of said body along said body to distribute a load therein throughout the length thereof and to discharge a load therefrom at the other end thereof, the improvement which consists of providing material-intercepting means inside said body at the material-receiving end thereof and wholly below the top of said body when in material-intercepting position for receiving and temporarily storing material delivered to said apparatus at the material-receiving end thereof while the major portion of the length of said body is unobstructed by said material-intercepting means and other material is being discharged from the body and means for moving said intercepting means to permit the passage of material stored thereby into the field of operation of the conveyor means and the access of further material delivered to said body at the first mentioned end thereof to the bottom thereof and to said conveyor means.

2. In an apparatus of the character described, including a body having side walls and providing a single compartment open from end to end for receiving and storing material and conveyor means associated with said body and extending along the bottom of said body inside the latter for moving material received at one end of said body along said body to distribute a load therein throughout the length thereof and to discharge a load therefrom at the other end thereof, the improvement which consists of providing, above the level of the conveyor and at the material-receiving end of said body only, material-intercepting means wholly below the top of said body and cooperating with the side walls of said body to provide a space for receiving and temporarily storing material delivered to said apparatus while other material is being discharged from the major portion of said body and means for withdrawing said intercepting means in a path wholly below the top of said body to permit the descent of material stored thereon into the field of operation of the conveyor means and the access of further material delivered to said body at the first mentioned end thereof to the bottom thereof and to said conveyor means.

3. In an apparatus of the character described, including a body having upwardly diverging side walls and open from end to end to provide a unitary compartment for receiving and storing material and conveyor means associated with said body and extending along the bottom of said body inside the latter for moving material received at one end of said body along said body to distribute a load therein throughout the length thereof and to discharge a load therefrom at the other end thereof, the improvement which consists of providing material-intercepting means projected through said side walls near the bottom of the latter horizontally into said body at the material-receiving end only thereof, above the conveyor for receiving material delivered to said apparatus

5 while other material is being discharged from the major portion of the length of the body and means for withdrawing said intercepting means to permit the descent of material stored thereon into the field of operation of the conveyor means and the access of further material delivered to said body at the first mentioned end thereof to the bottom thereof and to said conveyor means.

4. In an apparatus of the character described, including a body open from end to end to provide a unitary compartment for receiving and storing material and conveyor means associated with said body and extending along the bottom of said body inside the latter for moving material received at one end of said body along said body to distribute a load therein along the length thereof and to discharge a load therefrom at the other end thereof, the improvement which consists of providing material-intercepting means including 15 relatively movable elements projected from either side of said body into the latter above the conveyor for receiving material delivered to said apparatus at the material-receiving end thereof while other material supported by said conveyor 20 means over the major portion of the length of said body and of a depth exceeding the distance between said elements and the conveyor means is being discharged from the body and means for withdrawing said intercepting means laterally of said body, a portion through each side of the latter, to permit the descent of material stored thereon into the field of operation of the conveyor means and the access of further material delivered to said body at the first mentioned end 25 thereof to the bottom thereof and to said conveyor means.

5. In an apparatus of the character described, including a body open from end to end for receiving and storing material and conveyor means associated with said body and freely accessible 40 through an open end of the latter to material delivery means and extending along the bottom of said body inside the latter for moving material received at said end of said body along said body to distribute a load therein throughout the length thereof and to discharge a load therefrom at the other end thereof, the improvement which consists of providing, above the level of the conveyor, material-intercepting means projectible 45 into said body only at the material-receiving end of the latter for receiving material delivered to said apparatus while other material is being discharged from the remaining, major, portion of said body, said intercepting means including a pair of oppositely slidable plates selectively positionable to meet at the longitudinal center line of said body or to be at least substantially withdrawn oppositely through the sides of said body, and means for so positioning and withdrawing 50 said plates including hydraulically operated means at either side of said body for shifting said plates transversely of said body.

6. In an apparatus of the character described, including a body open from end to end to provide 55 a unitary compartment for receiving and storing material and conveyor means associated with said body and freely accessible, through an open end of said body, to material delivery means and extending along the bottom of said body inside the latter for moving material received at one end of said body along said body to distribute a load therein throughout the length thereof and to discharge a load therefrom at the other end thereof, the improvement which consists of providing, 60 above the level of the conveyor, material-inter-

cepting means for receiving material delivered to said apparatus while other material is being discharged from the body and means for selectively positioning said means to receive material and withdrawing said intercepting means to permit the descent of material stored thereon into the field of operation of the conveyor means, said intercepting means including a pair of oppositely slidable plates selectively positionable to meet at the longitudinal center line of said body along a line close to said conveyor and near the bottom of the compartment and extending from the material-receiving end of the latter to a point less than half the length of the compartment from that end, or to be at least substantially withdrawn, one through each of the sides of said body, and said positioning and withdrawing means including link and lever mechanism and hydraulic operating means therefor at either side of said body for shifting said plates bodily transversely of said body.

7. In an apparatus of the character described, including a body providing a hopper for receiving and storing material and conveyor means associated with said body and extending along the bottom of said body within said hopper for moving material along said body to distribute a load therein and to discharge a load therefrom, the improvement which consists of providing, above the level of the conveyor at the receiving end of said body, material-intercepting means for receiving material delivered to said apparatus while other material is being discharged from the body and means arranged wholly outside of said hopper for selectively extending and withdrawing said intercepting means to control the access of material to the field of operation of the conveyor means, said intercepting means relatively short, longitudinally of said body, and relatively low therein, so that a material load in said body deeper than the top of said intercepting means and of materially greater length than that of said intercepting means can be discharged while said intercepting means is interrupting access of new material to said conveying means.

8. In combination, material-receiving, storing and discharging means including means forming a hopper having a bottom and a conveyor of extended length and within said hopper and traversing said bottom, and material-intercepting means arranged adjacent the material-receiving end only of said conveyor and relatively short compared with the length of said hopper and projectible into said hopper above but near the bottom of the latter and in overlying relation to said end of said conveyor for temporarily storing material out of access to said conveyor while the major portion of the latter clears itself, including an intercepting device wholly below the top of said hopper and means for moving it between material-intercepting position and a position in which material may be discharged to the conveyor without substantial interference from said intercepting device.

9. In combination, material-receiving, storing and discharging means including a body providing a single elongated chamber having a bottom adapted to support a load of material and an elongated, circulating conveyor having a discharge run moving within said chamber over the bottom thereof, and material-intercepting means arranged adjacent the material-receiving end only of the discharge run of said conveyor and adapted to overlie a portion—less than half—thereof for temporarily storing material in said

chamber but out of access to said conveyor while the latter clears itself, including an intercepting device located wholly below the top of said chamber and means for moving it between a material-intercepting position and a position in which material may be discharged to the conveyor without substantial interference from said intercepting device.

10. In an apparatus of the character described, including a body having a compartment for receiving and storing material and conveyor means associated with said body and extending along said body at the bottom thereof for providing the bottom of said compartment and for receiving and moving material received at one end of said body along said body to distribute a load within said compartment throughout the length thereof and to discharge a load therefrom at the other end of said body, the improvement which consists of providing wholly within said compartment both as regards disposition between the sides and as regards disposition below the top thereof, above the level of the conveyor and at the receiving end only of said body, material-intercepting means for stopping the flow of material to said conveyor means while other material previously received by said conveyor and stored within said compartment over a length substantially exceeding the length of said intercepting means is being discharged from said compartment at the other end of said body.

11. In an apparatus of the character described, including a body having walls bounding a compartment for receiving and storing material and conveyor means associated with said body and extending along said body at the bottom thereof for providing the bottom of said compartment and for receiving and moving material received at one end of said body along said body to distribute the material within said compartment throughout the length thereof and to discharge the material therefrom at the other end of said body, the improvement which consists of providing, wholly within said compartment, above the conveyor, and at the receiving end only of said body, material-intercepting means for temporarily interrupting the flow of material from said receiving end of said body to said conveyor and storing it in a space bounded laterally by the walls of said body and beneath by said intercepting means while the material previously received by the conveyor and distributed thereby in said compartment over a length substantially exceeding the length of said space is discharged from said compartment at the other end of said body.

12. In an apparatus of the character described, including a body for receiving and storing material, said body open from top to bottom and from end to end to provide a single continuous chamber, and having side walls and a receiving end open for the free extension thereover of means for discharging material into said body, and conveyor means associated with said body and extending along the bottom of said body inside the latter for moving material received at the material-receiving end of said body along said body to distribute a load therein throughout the length thereof and to discharge a load therefrom at the other end thereof, the improvement which consists of providing material-intercepting means extending within said body, and below the top of the side walls of said body, and overlying said conveyor means only at the end of the latter remote from the discharge, for receiving and tem-

porarily storing all of the material delivered to said apparatus over the end wall thereof while other material previously received is being discharged from the body from the major portion of the length of the latter, and means for moving said intercepting means to permit the passage of material stored thereby into the field of operation of the conveyor means and the access, past said intercepting means, of all further material delivered to said body at the receiving end thereof to the bottom thereof and to said conveyor means.

13. Apparatus as defined in claim 12, wherein said intercepting means includes relatively movable plates parting at the center line of said body and separable to permit the passage of material stored upon them between them and to clear the whole width of the conveyor.

14. In a low height vehicle for receiving, storing and discharging material in underground mines, a mobile body of low height and of elongated generally rectangular shape, mobile supporting means for said body on which the latter is mounted in a relatively low position with its bottom located relatively close to the mine floor, said body having a material-receiving compartment of relatively large capacity extending lengthwise thereof throughout its length and for substantially its full height, an endless conveyor extending along the bottom of said compartment for aiding in the storing and distribution of material in said compartment and for discharging stored material from said compartment, said compartment having hopperlike sides extending upwardly and laterally at the sides of said conveyor out to the full width of said body, and adjustable plate means arranged on said body at the sides of said conveyor near one end portion of the latter and when in operative position close-

ly overlying the top run of said conveyor portion, said plate means when in retracted, inoperative position disposed at the sides of said conveyor below the hopper-like sides of said compartment,

5 said plate means movable inwardly into said operative position within said compartment wherein said plate means overlies said conveyor to completely shroud the top run of said conveyor along said end portion of the latter, the unshrouded portion of said conveyor substantially exceeding in length the length of the shrouded portion and being operable to discharge material stored in said compartment longitudinally beyond said plate means from said compartment at one end 15 of said compartment, and said plate means when in shrouding position receiving material discharged into the opposite end of said compartment whereby the latter may store material during such discharge of the material by said unshrouded portion of said conveyor.

10 15 20 25 20 25 15. A vehicle as set forth in claim 14 wherein power operated mechanism is carried by said body for moving said plate means inwardly into shrouding position above said conveyor and for retracting said plate means and includes power devices disposed beneath said hopper-like sides of said compartment.
